(57) **CLAIM**

The ornamental design for a folding gift box, as shown and described.

DESCRIPTION

FIG. 1 is a front, top perspective view of a folding gift box, showing my new design;
FIG. 2 is a rear, bottom perspective view thereof;
FIG. 3 is a front, top perspective view of the folding gift box, shown in an alternative position;
FIG. 4 is a front elevation view of the folding gift box;
FIG. 5 is a rear elevation view thereof;
FIG. 6 is a left side elevation view thereof;
FIG. 7 is a right side elevation view thereof;
FIG. 8 is a top plan view thereof;
FIG. 9 is a bottom plan view thereof;
FIG. 10 is a front view of the folding gift box, shown in an unfolded configuration;
FIG. 11 is a rear view thereof;
FIG. 12 is a left side elevation view thereof;
FIG. 13 is a right side elevation view thereof;
FIG. 14 is a top plan view thereof; and,
FIG. 15 is a bottom plan view thereof.

1 Claim, 15 Drawing Sheets
